UNITED STATES PATENT OFFICE.

JAMES F. MAYS, OF BIRMINGHAM, ALABAMA, ASSIGNOR TO MAYS ACCOUNTING MACHINE COMPANY, OF ASHEVILLE, NORTH CAROLINA, A CORPORATION OF NEVADA.

CALCULATING-MACHINE.

1,127,061.

Specification of Letters Patent.

Patented Feb. 2, 1915.

Application filed May 11, 1914. Serial No. 837,774.

To all whom it may concern:

Be it known that I, JAMES F. MAYS, a citizen of the United States, residing at Birmingham, in the county of Jefferson and

5 State of Alabama, have invented certain new and useful Improvements in Calculating-Machines, of which the following is a specification.

This invention relates more especially to 10 improvements in that class of calculating machines which employ a keyboard and a series of registering dials, and the primary object of the invention is to simplify the construction and lessen the cost of manufacture 15 of such machines without sacrificing efficiency or accuracy, and this is effected mainly by the simplification of the way in which the operation of carrying is done. Generally in machines of this class there is 20 an interconnection between the successive registering dials on which the numbers are set up, by which interconnection a number is carried from a dial of a lower to one of a higher denomination, such operation being 25 carried on between the registering dials on which the final result is shown. One way of effecting motion from one such dial to another is through the use of spring actuated escapement mechanism.

30 In my improved machine, the main registering dials do not carry at all, the carrying being done on a supplementary set of dials which display only the amounts carried. The final result is then obtained, in 35 the case of addition, for example, by merely adding to the amounts displayed by the main dials, the amounts shown by the carrying dials, by striking keys in columns and of denominations corresponding to the numbers 40 displayed on the carrying dials. By such an arrangement a great deal of the more or less complex carrying mechanism hitherto employed in machines of this class is entirely avoided.

45 In my machine the several sets of dials are so arranged with respect to each other, and with respect to the columns of keys, that the operation of the machine is purely mechanical and may be performed with 50 great facility and accuracy.

My improved machine possesses the further advantage that while extremely simple in construction is susceptible to full duplex operation, that is to say, the numbers 55 may be set up on the dials by striking

keys in several columns simultaneously. Usually machines which may be operated in this manner employ more or less complex mechanism.

My invention also contemplates the use, 60 in connection with the above mentioned dials, of a set of proving dials, which at each key stroke indicates the figure to be set up, and which serve, as will hereinafter more readily appear, as a very useful adjunct in 65 the operation of this machine.

In order to more fully describe my invention, reference will be had to the accompanying drawings which show one specific embodiment thereof, and in which,

Figure 1, represents said machine in top plan; Fig. 2, an enlarged fragmentary detail side elevation, partly in section, of the carrying dial stepping mechanism; Fig. 3, a vertical section on line 2^x—2^x; Fig. 2, with 70 parts removed; Fig. 4, a fragmentary horizontal section through the machine casing and keys, showing the interior mechanism in top plan; Fig. 5, a fragmentary section on line 5^x—5^x; Fig. 4, looking in the direction 75 of the arrow; Fig. 6, a fragmentary sectional elevation on line 6^x—6^x; Fig. 4, looking in the direction of the arrow; Fig. 7, a fragmentary section on line 7^x—7^x; Fig. 6, looking 80 in the direction of the arrow; Fig. 8, an 85 enlarged detail sectional elevation taken on line 8^x—8^x; Fig. 4, looking in the direction of the arrow, and, Fig. 9, a fragmentary detail section on line 9^x—9^x; Fig. 4, looking in the direction of the arrow.

The machine here shown comprises, 90 among other parts, a series of columns of keys 1, upon the finger tips of which appear the digits corresponding to the several keys as usual in this class of machines, said digits in the machine here shown reading, from one 95 to nine, inclusive, in each column commencing with the lowermost key in each column or the one nearest the operator, and no

In the accompanying drawings, I have shown the machine as provided with eight 100 columns of keys, but this number is purely arbitrary, since any desired number of columns may be employed. The stems of the keys extend through slots in and are guided for vertical movement by plates 2 105 and 3 supported upon two cross-plates 4 and 5 which form portions of the frame of the machine. Each key in traveling downward does so against the tension of a coil spring 6 which returns the key to its normal 110

position, the return movement of each key being limited by a stop pin 7 thereon engaging plate 2.

For each column of keys there is a master rock shaft 8, said shafts being journaled for rotation in plates 4 and 5. These shafts are adapted to be rotated or rocked individually on their longitudinal axes a given amount whenever any key in a corresponding column is pushed down its full stroke, each key in the column, however, rotating the shaft a different amount. For example, the full downward stroke of a "1" key will rotate its corresponding shaft 8 a given amount; the full downward travel of a "2" key will turn its shaft 8 twice as far as the "1" key, and so on with the keys of the respective columns to the "9" keys which rotate the shafts 8, nine times as far as do the "1" keys. Such movement may be transmitted from the keys to the rock shafts in a variety of ways. For example, each rock shaft 8 may carry a series of rocker arms 9 fast thereon, and all set to occupy corresponding angular positions in the normal position of the shafts, while the key stems carry lugs 10 fast thereon and so disposed as to engage and rock the arms 9 on the downward travel of the keys. By having each key travel downward the same amount for its full stroke, which may be effected by having the lower ends of all the keys the same distance from the bottom plate 11 of the machine in their normal positions, and adapted to strike said plate at the lower limit of their travel, it becomes an easy matter to regulate the amount of throw imparted to the shafts 9 by the keys by the disposition of the lugs 10 which engage the rocker arms. For example, the lug 9 of the "9" key would occupy the position shown on the key on the right Fig. 6, the lug on the "8" key would be slightly higher up as shown on the key on the left in said figure, and so on to the "1" key which would have to travel nearly its entire stroke before its lug 9 would engage its rocker arm. The rock shafts 8 are thus rotated by the keys, each against the tension of an individual coil spring 12 by which they are returned to normal and each stopped in the position of rest by a stop lug 13 fast thereon engaging a stop pin 13' on the frame of the machine. For each of the rock shafts 8 there is a dial shaft 14, said dial shafts being journaled in two transverse plates 15 and 16 supported in any desired way between the sides 17 and 18 of the machine.

Each dial shaft 14 carries fast thereon a number registering dial 19 having a series of numbers "0" to "9" equally spaced around its periphery. Rotation is imparted to these dials from the rock shafts 8 by the following mechanism: Each rock shaft 65 extends through plate 5 and carries on its

end a gear 20 fast thereto, and each of these gears meshes with a pinion 21 fast on a sleeve 22 rotatable each on one of the dial shafts. Fast on or integral with each of these sleeves is a disk 23 which carries an annular spring pawl 24 which engages with the teeth of a ratchet 25 fast on each dial shaft. The gears 20 and 21 are so proportioned that for each full key stroke the dial 19 corresponding to the column in which the key struck is located, will rotate through an arc sufficient to bring the number on that dial corresponding to the number on the key struck, into the display position which in the case shown is in the vertical plane of the axis of the dial shaft and above the same, where said numbers may be seen through openings 26 in the top plate 27. When the operated key is released, its shaft 8 rotates backward under the action of spring 12 and in so rotating causes the corresponding ratchet 24 to travel back each time to its normal position. The dials 19, however, remain in their set positions until one of their corresponding keys is again struck, said dials being prevented from rotating backward by ratchets 28 fast on shafts 14 and engaging with holding pawls 29 pivoted on cross-plate 16.

For each dial 19 except the one on the right or the one corresponding to the units column of keys, there is a carrying dial 30. These carrying dials are all mounted for rotation around the axis of a common shaft 31 extending transversely across the machine at right angles to the axes of the dial shafts 14. The specific way of mounting these carrying dials here shown may be seen most clearly in Fig. 3. Each carrying dial is rotatable on a sleeve 32 fast in the upper end of an individual upright or standard 33 secured to the bottom of the machine, the shaft 31 passing through the axis of and rotatable as well as longitudinally slidable with respect to each of said sleeves. 110

Each sleeve 32 is provided with a flange 34 which engages the inner face of the web of the carrying dials to prevent lateral motion of the latter, the lateral motion of said dials in the opposite direction being prevented by the standard 33 engaging with ratchets 35, one of which is fast to the outer face of the web of each carrying dial, for purposes which will later more fully appear. 115

Each dial 30 carries upon its periphery a series of numbers from 1 to 30 in the case here shown, or from 1 to any other number if desired, with a zero or blank space, as may be desired, between the lowest and highest numbers. These numbers are adapted to be displayed through openings 36 in the top plate 27 to indicate the amount carried. 120

For operating the carrying dials the following mechanism is provided. As before stated, there is fast to each of the carrying 125

dials a ratchet 35. For each of these ratchets there is an actuating pawl 37, and each of these pawls is carried upon an individual arm 38 mounted for angular movement each 5 upon one of the sleeves 32. Each of these arms is connected through a pin and slot connection 39, 40 with an individual lever arm 41, and each of these lever arms is fast to an individual sleeve 42 adapted to rock on 10 a shaft 43 supported in the sides of the machine. Also fast to each of the sleeves 42 is a lever arm 44 and each of these arms rests at its free end upon a drop cam 45, one such cam being fast upon each of the 15 dial shafts 14. The cams 45 are so adjusted that when the dials 19 stand at zero, arms 44 rest upon the lowermost portion of said cams, and when said cams have rotated nine-tenths of a revolution, as they will do 20 upon the operation of a "9" key, the arms 44 rest upon the highest portion of the cams adjacent the drop so that on the next movement of the cam its arm 44 will pass the drop. On account of the position of the 25 dials 30 with respect to their corresponding cams 45, the free ends of all of the levers 44 except the one on the extreme right or the one engaging the units cam are bent at right angles and then down as shown most clearly 30 in Figs. 4 and 8.

The throw of cams 45 and the teeth of the ratchets 35 are so proportioned that for one complete rotation of a dial shaft 14 or its dial 19, the corresponding carrying dial will 35 rotate one-tenth of a revolution. In other words, while the dials 19 will rotate forward an amount corresponding to the number on the key operated in a column corresponding to a given one of such dials, the 40 depression of the same key imparts an angular movement to the dials 30 only one-tenth of that of the corresponding dials 19. Hence each key stroke imparts a separate movement to the two sets of dials at the same 45 time, the movement of the carrying dials being always one-tenth that of the main dials 19, in the machine here shown.

For the purpose of causing the dials 30 to display through their openings 36 only 50 the numbers carried, there is provided for each such dial a shield 46 extending partially around the circumference of said dials, and movable with respect to said dials circumferentially thereof by arms 38 to which 55 the respective shields are made fast, or formed on, each such shield being provided with an opening 47 to display the number carried. The arms 44 are held down over cams 45 under the tension of individual coil 60 springs 48. The function of the shields will be more fully appreciated after the operation of the machine has been described.

The operation of the parts thus far described is briefly as follows: So far as the 65 operation of the dials 19 is concerned, they

merely rotate independently of each other, each through an arc corresponding to the digit of the key operated in the corresponding column therewith. For example, if a "6" key is struck, the dial 19 operated from 75 that key will display the digit "6," and if thereafter without resetting said dial an "8" key be struck in the same column, the dial 19 will indicate "4." Since there is no connection between the column of keys operated 80 and the dials of the next higher denomination, there will be no carrying from one dial 19 to the next; in other words, these dials operate independently of each other.

The carrying is done entirely by the dials 85 30 in the following way: Each forward angular movement of a rock shaft 8 imparts a forward angular movement to its corresponding cam 45. Cam 45 in so rotating lifts the outer end of lever 44 resting thereon, and in so doing raises arm 38 and therefore imparts angular movement to the carrying dial in line with the column of keys of the next higher denomination and a corresponding angular movement to its shield 46, 90 so that if the dial started from its zero position, it will still display zero through opening 47. This movement of the dial and shield will continue as each key in the column with the first key operated is struck 95 until the drop of its cam 45 passes its lever 44 which causes said lever to descend and pull arm 38 back one tooth of ratchet 35, said arm carrying with it its shield 46, the opening 47 of which now displays the number carried, since the shield drops back only when a number is to be carried, or, in other words, when two keys in the same column are struck the sum of whose digits is ten or greater than ten, the cams 45 being 100 so proportioned that their drops pass the lever 44 on the last one-tenth of the rotation of a corresponding dial shaft 14. The dials 30 also have no connection one with the other as will be seen, each being operated 105 from the keys in a column of the next lower denomination, that is, the carrying dial for or in line with the thousands column of keys is operated from the keys of the hundreds column, the carrying dial in the hundreds 110 column is operated from the keys of the tens column, and so on.

The shields 46 prevent the display through openings 36 of any but the actual numbers carried. If stationary display 115 openings such, for example, as the openings 36 alone were employed, even assuring that they were as narrow, measured in a direction at right angles to the axis of dials 30, as openings 47, such openings instead of displaying in all cases the actual numbers carried, would display a portion of said numbers and a portion of the next preceding or succeeding numbers as the case may be. By having the numbers to be displayed fol- 120 125 130

lowed by the opening 47 of its shield, the number carried alone will be displayed since the body of the shield hides the other numbers. The outer display openings 36 are much longer than the shield openings 47 to allow for the travel of the latter without becoming obstructed. It will be readily seen that the load on the keys is extremely small, which will greatly lighten the finger stroke 10 necessary to operate the machine.

Let it be required to add 4793, 3546 and 2972. To set up the first number (4793), the operator strikes the "4" key in say the fourth column reckoning from the right, the "7" key in the next column on the right, the "9" key on the next column still on the right, and then the "3" key in the next column, proceeding preferably from left to right, as this is the logical though not necessary order. In a similar way he strikes keys in corresponding columns for the numbers 3546 and 2972. The dials 19 corresponding to the columns of keys operated will then display the numbers 9-1-0-1 respectively, as shown in Fig. 1, which will be the sum of the three amounts added, less the amounts carried, which latter amounts will be 2-2-1 displayed by the carrying dials above the figures 9-1-0-1 respectively, as shown in Fig. 1. Then by striking the keys corresponding to the numbers 2-2-1 in the columns of said keys in line with these numbers set upon the carrying dials, the amount carried will be added on the main dials 19, when the latter will display the true sum of 11311.

The main dials 19 and the carrying dials and openings 26, 36 are so arranged as to display their dial numbers in line with each other and with their respective columns of keys so that one may readily see at a glance just which figures are to be added to give the final result. This relation is especially useful with respect to the numbers of the carrying dials, since they display the numbers which are to be struck on the keys to give the final result, and it is a great aid to accurate operation to have the numbers in line with their respective key columns. This greatly lessens the liability of striking a key in the wrong column in getting the final result. It is also preferred that the key tops and display openings all be substantially in the same horizontal plane as here shown, though this is not essential.

Since the dials 19 are entirely independent in their operation, that is, the rotation of one does not effect the rotation of the other, the same holding true as to the dials 60-30, the machine may be operated by striking one key in several columns simultaneously, rendering the machine susceptible to duplex operation.

For the purpose of showing that any key 65 struck has been properly operated, that is,

sent down far enough to properly operate the dials 19 and 30, particularly the latter, I provide a set of proving dials 49 which may be formed by placing a circular band or flange on each of the ratchet disks 22. 70 These dials carry on their periphery numbers from 0 to 9 corresponding in angular position to those on dials 19, for which are provided eight openings 50 in the top of the machine. Whenever, therefore, any key 75 is sent down a full stroke, a number corresponding to that on the top of the key operated will be displayed through one of the openings 50, corresponding to the column of keys in which the one operated is situated. 80 If on the other hand, the number is not fully displayed through said opening, it will show that the key has not been fully operated, or if the number displayed through a given opening 50 does not correspond say to the number shown by one of the carrying dials in adding that number to the one shown on its corresponding dial 19, this will show that the wrong key has been struck. When the keys are released, however, the dials 49 return to zero, since they are fast to the pinions 21 which are positively geared to the key operated rock shafts 8. The openings 50 for these dials are also in line respectively with openings 26 and 95 36 and their respective key columns. These proving dials while useful are not an essential part of my machine, and may be dispensed with if desired. No extra mechanism is provided for resetting dials 19, since 100 they may be reset merely by striking the keys in their corresponding columns.

The mechanism for resetting the carrying dials to zero or normal is extremely simple. This resetting mechanism comprises, among 105 other parts, shaft 31 on which is made fast a series of arms 51, one for each of the carrying dials, and adapted to coöperate each with a pin 52 on its corresponding carrying dial (see Fig. 3). The shaft 31 may slide 110 laterally and is normally pushed to the right under the tension of a coil spring 53 (Fig. 1) so that the arms 51 are out of the paths of pins 52, and said shaft is normally under angular tension by said spring so that stop 115 pin 54 on said shaft engages a stop pin 55 on the machine frame or casing. To reset the carrying dials, shaft 31 is shifted to the left a sufficient amount to bring the arms 51 into the paths of pins 52, then rotated until 120 pin 54 is brought around into engagement with stop 55, when the dials will be returned to their initial or zero positions by the engagement of arm 51 with pins 52 on the dials. Shaft 31 is thus operated by a knob 125 56 on the outside of the machine, which when released allows the shaft to rotate backward to its normal position when pin 54 on the shaft will engage stop 55 and stop the rotation of the shaft. At the same time 130

the shaft 31 will be sent laterally to the right under the action of spring 33, thus disengaging arms 51 from the pins on the dials.

- For the purpose of preventing overthrow 5 of dials 19 the following or any other desired mechanism may be provided: On each dial shaft 14 there is mounted a stop ratchet 57 fast to shaft 14, for each of these ratchets there is provided a stop lever or pawl 58. 10 Each of these stop levers is fast on an individual supplementary rock shaft 59 one for each of the master rock shafts, and extending parallel thereto and journaled in plates 4 and 5. Each of these supplementary 15 rock shafts carries a series of arms 60 fast thereto, one for each key in its corresponding key column. These arms are adapted to be struck and operated by pins 61 fast on the respective keys so disposed that when any key is pushed down to its fullest extent, its pin 61 will engage an arm 60 just before the key reaches the end of its downward movement, when the corresponding shaft 59 will be rocked and send the nose of its stop lever 20 58 into position to engage a tooth of its ratchet 57 and stop said ratchet at the instant the key reaches the end of its stroke. The shafts 59 are returned each to its normal position by a coil spring 62. No claim 25 is here made to this overthrow mechanism, and any desired form may be used.

While I have here shown and described but one specific embodiment of my machine, it should be understood that the same is susceptible to many changes and modifications within the scope of my invention.

What I claim is:

1. A calculating machine, comprising a plurality of pairs of registering dials, a column of keys for each such pair of dials, and mechanism to control the rotation of said dials from said keys, one of said dials of each pair being controlled by the keys of a column of the same denomination therewith 45 only, and the other dial of the same pair being controlled by the keys in a column of the next lower denomination only, the latter dials registering only the amounts carried from a column of lower to one of a higher 50 denomination.

2. A calculating machine, comprising a plurality of pairs of registering dials, a column of keys for each such pair of dials, and mechanism to control the rotation of said 55 dials from said keys, one of said dials of each pair being controlled by the keys of a column of the same denomination therewith only, and the other dial of the same pair being controlled by the keys in a column of the 60 next lower denomination only, the latter dials registering only the amounts carried from a column of lower to one of a higher 65 denomination, the dials of each pair arranged to register their numbers in line with the respective columns of keys.

3. A calculating machine, comprising a series of columns of keys, said columns corresponding to units, tens, hundreds etc. denominations, a registering dial for each of said columns, and means for imparting angular movement to said dials from the keys of their respective columns only, a carrying dial for each of said key columns but the units column, and means to impart angular movement to said carrying dials 70 from the keys of a column of a next lower denomination, the said carrying dials being independently movable with respect to each other.

4. A calculating machine, comprising two sets of number registering dials, a plurality of columns of keys and key controlled means to impart simultaneous angular movement to one dial in each of said sets, but at different angular velocities, for the purpose set forth.

5. A calculating machine, having a series of number registering dials, each of which is independently rotatable with respect to the other, a column of keys for each of said dials, means controlled by said keys to impart angular movement to said dials varying according to the key in corresponding columns operated, and a series of carrying dials each of which is independently rotatable with respect to the other, and means common to each of said first named dials and a carrying dial of a next higher order or denomination for rotating both said dials but at different angular velocities.

6. A calculating machine, comprising a plurality of columns of keys, a rock shaft for each of said columns, means for imparting angular movement to said rock shafts from the keys of their respective columns, the said movement of said rock shafts varying according to the key in a column operated, a number registering dial for each of said rock shafts and means for rotating said dials from their corresponding rock shafts 105 and independently of each other, a series of carrying number registering dials, means individual to each of said carrying dials and operated by said rock shafts of a next lower denomination for rotating said carrying 110 dials independently of each other and at a different angular velocity from said first named registering dials.

7. A calculating machine, comprising a plurality of columns of keys, a rock shaft 120 for each of said columns, means for imparting angular movement to said rock shafts from the keys of their respective columns, the said movement of said rock shafts varying according to the key in a column operated, a number registering dial for each of said rock shafts and means for rotating said dials from their corresponding rock shafts and independently of each other, a series of carrying number registering dials, a cam in- 125

dividual to each of said carrying dials and operated each by a rock shaft of a next lower denomination, a ratchet fast to each of said carrying dials, a pawl for each of 5 said ratchets, means operated by each of said cams to operate said pawls for imparting rotation to said carrying dials each independently of the other.

8. A calculating machine, comprising a 10 plurality of columns of keys, a rock shaft for each of said columns, means for imparting angular movement to said rock shafts from the keys of their respective columns, the said movement of said rock shafts varying according to the key in a column operated, a number registering dial for each of 15 said rock shafts and means for rotating said dials from their corresponding rock shafts and independently of each other, a series of 20 carrying number registering dials, a cam individual to each of said carrying dials and operated each by a rock shaft of a next lower denomination, a ratchet fast to each of 25 said carrying dials, a pawl for each of said ratchets, means operated by each of 30 said cams to operate said pawls for imparting rotation to said carrying dials each independently of the other, and a shield individual to each of said carrying dials and movable by said cams to display one number at a time on said carrying dials.

9. A calculating machine, comprising a series of columns of keys, said columns corresponding to units, tens, hundreds etc. 35 denominations, a number registering dial for each of said denominations adapted each to display its numbers one at a time in line with their respective key columns, means operated by the keys of the respective columns to rotate said registering dials in line therewith, a carrying number registering dial for each of said key columns except the units column adapted each to display its 40 numbers one at a time in line with a column of said keys and the numbers registered by the other dials, and means controlled by keys in the respective columns for imparting rotation to the carrying dials in line with a key column of a next higher 45 denomination.

10. A calculating machine, comprising a series of columns of keys, said columns corresponding to units, tens, hundreds etc. denominations, a number registering dial for 55 each of said denominations adapted each to display its numbers one at a time in line with their respective key columns, means operated by the keys of the respective columns to rotate said registering dials in line therewith independently of the others, a carrying number registering dial for each of 60 said key columns except the units column adapted each to display its numbers one at

a time in line with a column of said keys and the numbers registered by the other 65 dials, and means controlled by keys in the respective columns for imparting rotation to the carrying dials in line with a key column of a next higher denomination, the rotation of each of said carrying dials being 70 independent of that of any of the other carrying dials.

11. A calculating machine, comprising a series of columns of keys, said columns corresponding to units, tens, hundreds etc. denominations, a number registering dial for each of said denominations adapted each to display its numbers one at a time in line with their respective key columns, means operated by the keys of the respective columns to rotate said registering dials in line therewith, a carrying number registering dial for each of said key columns except the units column adapted each to display its 80 numbers one at a time in line with a column of said keys and the numbers registered by the other dials, and means controlled by keys in the respective columns for imparting rotation to the carrying dials in line with a key column of a next higher denomination, 85 and a series of number registering dials arranged to display their numbers in line with the column of the operated key, and in line with the numbers displayed by the other dials corresponding to the same column, said 90 last named dials returning to their initial positions each on the releasing of the key operating it.

12. A calculating machine, comprising a plurality of columns of keys, a rock shaft 100 for each of said columns, means for imparting angular movement to said rock shafts from the keys of their respective columns, the said movement of said rock shafts varying according to the key in a column operated, a number registering dial for each of 105 said rock shafts and means for rotating said dials from their corresponding rock shafts and independently of each other, a series of carrying number registering dials, a series 110 of cams, one for each of said carrying dials and each operated by an individual rock shaft, a ratchet fast to each of said carrying dials, a pawl for each of said ratchets, an angularly movable arm for each of said 115 carrying dials for supporting their respective pawls, and a series of lever arms, one engaging each of said cams and operatively connected to the pawl carrying arm of an adjacent carrying dial.

In testimony whereof I affix my signature in presence of two witnesses.

JAMES F. MAYS.
